UNITED STATES PATENT OFFICE.

GEORGE F. EBERHARD, OF CLEVELAND, OHIO.

HARNESS-TERRET.

SPECIFICATION forming part of Letters Patent No. 244,207, dated July 12, 1881.

Application filed May 7, 1881. (No model.)

To all whom it may concern:

Be it known that I, GEORGE F. EBERHARD, a citizen of the United States, resident of Cleveland, in the county of Cuyahoga and State of Ohio, have invented a new and valuable Improvement in Harness-Terrets; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation of the whole device; and Figs. 2, 3, and 4 are detail views of various parts of the same.

This invention has relation to drop-terrets for harness; and it consists in the construction and novel arrangement of the base cast in one piece with lugs on its under side and with a bearing on top adapted to bend over the ring in hook form, and, in connection therewith, of the base-screw and shouldered ring, as herein-after set forth.

In the accompanying drawings, the letter A designates the terret-ring, which is reduced at a in its lower portion, between the shoulders b, forming a bearing-bar.

B indicates the base of the terret, which is

cast with the lugs c on its bottom, on opposite sides of a central hole, d, which is designed to be threaded for the reception of the end of the terret-screw D. On its upper surface the base is cast with a projection or bearing, e, to bend down over the bar a of the ring and form a bearing therefor, connecting the ring and base. This bearing or hook e is designed to have parallel ends g, to engage the shoulders b of the ring when the bearing-bar a is in place.

Having described this invention, what I claim, and desire to secure by Letters Patent, is—

1. A drop-terret consisting of the ring A and the base B, having the lugs c and screw D, substantially as specified.
2. The terret-base cast with the projection or hook e, to bend down over the terret-ring, substantially as specified.
3. The combination, with the ring A and its bearing-bar a, of the base B, its hook e, lugs c, and screw D, substantially as specified.

In testimony that I claim the above I have hereunto subscribed my name in presence of two witnesses.

GEORGE F. EBERHARD.
